(57) **CLAIM**

The ornamental design for a watch dial face, as shown and described.

DESCRIPTION

FIG. 1 is a perspective view of a watch dial face according to my new design.

FIG. 2 is a top plan view of the watch dial face of FIG. 1.
FIG. 3 is a side elevational view of the watch dial face of FIG. 1.

FIG. 4 is a back plan view of the watch dial face of FIG. 1.
FIG. 5 is a side elevational view of the watch dial face of FIG. 1.

FIG. 6 is a bottom plan view of the watch dial face of FIG. 1; and,

FIG. 7 is a front plan view of the watch dial face of FIG. 1.
The broken line showings of FIGS. 1-7 are for illustrative purposes only, and form no part of the claimed design.
